QUICK CHANGE RANGE EXTENDER SYSTEM FOR TV ZOOM LENS

Wayne D. Clegg, 6604 Valmont St.,
Tujunga, Calif. 91042

Filed Feb. 22, 1973, Ser. No. 334,715

Term of patent 14 years

Int. Cl. D16—05

U.S. Cl. D61—1 E

Fig. 4

Fig. 5

Fig. 6

Fig. 7

FIG. 1 is a right front perspective view of a quick change range extender system for TV zoom lens showing my new design at nearly its fully extended position;

FIG. 2 is a left side elevational view thereof;

FIG. 3 is a top plan view thereof;

FIG. 4 is a front end view thereof;

FIG. 5 is a rear end view thereof;

FIG. 6 is a bottom plan view thereof; and

FIG. 7 is a right front perspective view thereof at nearly its minimum extension position.

I claim:

The ornamental design for a quick change range extender system for TV zoom lens, substantially as shown and described.
